SHOCK RESISTANT ELECTRIC SWITCH

Clarence W. Kuhn, Wauwatosa, and Theodore F. Rosing, Whitefish Bay, Wis., assignors to Cutler-Hammer, Inc., Milwaukee, Wis., a corporation of Delaware

Application November 28, 1951, Serial No. 258,586

16 Claims. (Cl. 200—124)

1

This invention relates to electric switches, and more particularly to a manually operable shock resistant starter switch.

An object of the invention is to provide a starter switch constructed to remain in either open or closed switching position until manually actuated to the opposite position, said switching positions being maintained despite the occurrence of high intensity percussion such as results from large explosions and the like.

Another object is to provide a compact switch of a construction permitting overload current responsive devices to be incorporated therein in a unitary manner for minimized possibility of misalignment due to shock, and permitting said overload devices to be reset by the manually operable switch actuating means.

Another object of the invention is to provide a switch embodying a shock resistant combination of balanced lever type latch means to insure maintenance of the switch in a first circuit controlling condition and spring loaded actuating means to effect unlatching operation of the latch means and operation of the switch to a second circuit controlling condition.

A further object is to provide means to achieve a predetermined wear allowance in the contactors of the switch regardless of variations in the construction of the switch as a result of manufacturing tolerances.

The switch, in general, comprises an electrical contact assembly, a link system movable to effect shifting of the contact assembly to various switching positions, and a balanced lever system including latch portions adapted to latch the link system and contact assembly in predetermined positions regardless of extraneous forces such as percussive shock. The balanced lever system and latch portions are adapted to be actuated to unlatching position both by manual means and by devices responsive to the flow of an overload current in a circuit controlled by the contact assembly, so that shifting of the link system and contact assembly may be effected either manually or automatically. In order to facilitate achievement of the proper wear allowance in the movable contactor elements of the contact assembly, indexing and adjusting means are provided to permit a predetermined initial adjustment of the stationary portions of the contact assembly relative to the frame on which the link system is mounted.

Other objects and advantages of the invention will be set forth more fully in the following de-

2

scription of an embodiment of the invention illustrated in the accompanying drawings.

In the drawings:

Figure 1 is an enlarged front elevation illustrating the switch in closed position, with portions being broken away to better illustrate the structure;

Fig. 2 is a vertical section taken generally along line 2—2 of Fig. 1;

Fig. 3 is a section on line 3—3 of Fig. 1;

Fig. 4 is a sectional view taken along line 4—4 of Fig. 1 and looking in the opposite direction from Figs. 2 and 3;

Fig. 5 is a partial horizontal section taken generally along line 5—5 of Fig. 1;

Fig. 6 is a side elevational view, partially schematic and partially in section, showing the positions of the parts after actuation thereof to circuit opening position by the left current responsive overload device in Fig. 1;

Fig. 7 is an enlarged detail view, primarily in horizontal section, illustrating the ratchet and solder elements of one of the overload devices;

Fig. 8 is an enlarged detail view showing the relation between a ratchet member and the corresponding lever member of the left overload device;

Fig. 9 is a rear elevation showing the switch in closed position, with portions broken away to illustrate the contact and contactor elements; and

Fig. 10 is a sectional view taken on line 10—10 of Fig. 9, showing the switch in closed position and illustrating the shim adjustment and reference means utilized to achieve the proper wear allowance in the contactor means.

Referring to the drawings and particularly to Figs. 1 and 10 thereof, the various operating components of the starter switch are mounted on and within a frame which is illustrated as comprising a generally rectangular base or mounting plate 1, a pair of spaced parallel side plates 2 projecting upwardly vertically from the base plate 1 and secured thereto as by screws 3 provided through outwardly extending flange portions 4 of the side plates, and a channel member 5 capped over the upper edges of the side plates 2 and connected thereto by suitable screws. The frame and all of the elements mounted thereon are adapted to be covered by a casing, not shown, which serves to protect the switch from dripping water and other harmful conditions which may be encountered in service.

As best shown in Figs. 1 and 6, the various elements 1, 2 and 5 of the frame form a rectangular

chamber adapted to contain intermediate or link means which operably connects a pair of switch actuating members 6 and 7 with an electrical contact assembly 8. The front actuating member 6, comprising a vertical arm bar 9 having a push button 10 at the upper end thereof, is adapted when manually depressed to effect actuation of the contact assembly 8 to "stop" or circuit opening position, whereas the similarly constructed rear actuating member 7 serves when depressed to effect actuation of the contact assembly to "start" or circuit closing position.

The intermediate or link means connecting the actuating elements 6 and 7 with contact assembly 8 includes a vertically disposed pair of generally disc shaped cam plates 11 and 12 and a horizontal lever member 13 (Fig. 3), the latter being associated through cam means with the cam plates 11 and 12 and serving to operate the contact assembly 8 upon forward and reverse rotation of the cam plates by the actuating members 6 and 7. The cam plates are pivotally mounted at approximately their centers on a principal axle rod 14 which extends between the mid portions of the side plates 2 and is secured as by cotter pins against axial shifting movement. In order to rigidly interconnect the left cam plate 11 (Fig. 1) with the right cam plate 12 and maintain the same in spaced parallel relation, three members 15, 16 and 17, respectively, are provided between the plates 11 and 12 secured thereto by riveting.

Referring particularly to Figs. 1 and 3, the horizontal lever 13 is formed of two generally arcuate side members 18 having their forward ends pivoted to a suitable fulcrum pin 19 which is mounted between the frame side plates 2 forwardly of the lower cam plate edges. From the fulcrum pin 19, the side members 18 extend rearwardly between the lower portions of the cam plates 11 and 12 for insertion into the contact assembly 8, with a roller 20 being journaled at the rear ends of the side members 18 for the purpose of engaging a slide bar portion 21 of the contact assembly. The roller 20 additionally serves, together with a cam pin 22 and with a spacer member 23 on fulcrum pin 19, to hold the side members 18 of lever 13 in spaced relation.

The cam pin 22 is disposed at the relatively elevated central portion of lever 13 and is shaped with a thick center portion located between side members 18 and with two relatively thin end portions extending laterally through the side members in the manner of a trunnion. Each of the end portions of the cam pin is inserted through one of a pair of corresponding arcuate cam slots 24 in the lower portions of cam plates 11 and 12. The slots 24, as best shown in Fig. 3, slant upwardly and forwardly so that the cam pin 22 is elevated to effect upward pivot of lever 13 when the plate members 11 and 12 are rotated forwardly, or clockwise in Fig. 3, and is lowered to effect downward pivot of lever 13 upon reverse rotation of the plate members.

As previously indicated, the necessary forward and reverse rotation of the cam plates 11 and 12 to cause upward and downward pivot of lever 13 is effected, respectively, by the front and rear actuating members 6 and 7. For this purpose one of the rivet members 15 which connect the cam plates is located forwardly of axle member 14 and passes through a vertical slot 25 in the arm bar 9 of front actuating member 6. Another rivet member 16, located diametrically opposite member 15, passes through the lower end of the arm

5 bar 9 of rear actuating member 7. The third rivet member 17 is located between the upper portions of the cam plates and serves, in addition to its spacing function, to stabilize the plates 11 and 12 against wobbling. Suitable spacing washers, not shown, are provided between the respective arm bars 9 and the cam plates to hold the bars in position.

With the described construction wherein the arm 9 of front actuating member 6 is slotted to receive rivet member 15, a lost motion connection is provided which effects forward rotation of cam plates 11 and 12 only when the front arm 9 is in engagement with rivet 15 at the upper end of the slot 25. The purpose of the lost motion connection is to permit the front actuating member 6 to be employed, as will be described in detail subsequently, to reset a pair of overload current responsive devices 26 and 27 after operation thereof. Since it performs no resetting function, the rear actuating member 7 is connected to rivet member 16 without lost motion and is substantially shorter than the front member 6.

Although the front and rear actuating members 6 and 7 are adapted to effect actuation of the lever 13 and contact assembly 8 as previously set forth, it is a principal feature of the invention that such actuation can only occur in a snap-action manner and only when the members are manually depressed as distinguished from being jarred by percussive shock and the like. To achieve such shock resistant and snap-action characteristics, left and right balanced lever and latching assemblies 28 and 29 (Fig. 1) are provided outwardly adjacent the respective cam plates 11 and 12, and compression springs 30 are provided between the respective actuating arms 9 and button members 10 for spring loading and lost motion action as will be described hereinafter.

40 The balanced lever assemblies 28 and 29 which lock the switch in the desired positions are substantially identical to each other and are mounted in reversed manner on axle member 14 so that the left assembly 28 may serve to latch the switch in circuit opening position and the right assembly 45 29 in circuit closing position. Referring to Fig. 2 wherein the right balanced lever system 29 is illustrated, each system comprises upper and lower horizontal lever links 31 and 32, a main horizontal lever 33 including two spaced parallel tapered members pivotally mounted at their centers on axle member 14, and forward and rear vertical link bars 34 and 35 which operably associate the horizontal lever links 31 and 32 with main lever 33. The vertical link bars 34 and 35 are pivotally connected, respectively, to the centers of the horizontal lever links 32 and 31 and to the centers of the forward and rear arms of main lever 33. In addition, the outer ends of the lever links 31 and 32 are pivoted on studs 36 which project inwardly from the associated frame side plate 2. In order to improve the stability of the lever systems 28 and 29 under shock conditions, each horizontal lever link is formed, similarly to the case of main lever 33, of two components which are held in spaced parallel relation by a pivot stud 36 and also by an end of the associated vertical link bar.

45 The lever links 31 and 32, as well as main lever 33 and the vertical link bars 34 and 35, are balanced with respect to weight, shape, size, and lever ratios so as to form two portitons of substantially the same shock susceptibility. Accordingly, if a shock wave is traveling, for example, in a downward direction in Fig. 2 it will

strike one such portion comprising the upper lever link 31, the rear vertical bar 35, and the left or rear arm of the main lever 33 and will tend to pivot the latter counterclockwise. The same shock wave, however, will also strike the second such portion comprising the right arm of lever 33, the forward vertical bar 34, and the lower lever link 32 and will tend to pivot the main lever 33 in a clockwise direction. Since the various members are balanced, the pivotal forces acting on main lever 33 will cancel each other and the resulting movement in the system will be zero.

According to the invention, each shock resistant balanced lever system has associated therewith a latch pin or lug 37 mounted at the inner end of the upper lever link 31 opposite pivot stud 36. Each of the latch pins 37, which are secured as by riveting to the two components of the lever link, projects inwardly into either a circumferential slot 38 in the associated cam plate 11 or 12 or into a communicating radial slot 39 or 40 therein, depending, as shown in Figs. 3 and 4, upon the relative positions of the cam plates and lever systems. The circumferential slots 38 of the two cam plates 11 and 12 are correspondingly located a slight distance from the upper edges of the plates. The radial slots 39 and 40 on the other hand, do not correspond in location but instead extend radially to the extreme cam peripheries from opposite ends (Fig. 6) of the circumferential slots 38 with which they communicate.

As shown in Fig. 3, the radial slot 40 in the right cam plate 12 is located at the forward end of the associated circumferential slot 38. Since the cam plates are illustrated in Fig. 3 as being in reverse or counterclockwise rotated position effecting closing of the switch, the radial slot 40 in right cam plate 12 is shown as registering with the latch pin 37 of the right balanced lever assembly 29. In order to bias the pin 37 into latching position within radial slot 40 once such registry is attained, a pair of helical tension springs 41 (Fig. 2) are provided, respectively, between the pivot studs 36 and pins 42 extending between the components of main horizontal lever 33 at the opposite tapered ends thereof. The tension springs 41 cooperate in effecting clockwise pivot of the main lever 33 and consequent counterclockwise pivot of upper lever link 31 and elevation of latch pin 37 into radial slot 40. Additional undesired elevation of latch pin 37 is prevented by the engagement of inwardly extending pairs of vertically spaced stop arms 43, one of the pairs being formed integral with the forward vertical link bar 34 and the other pair with the rear vertical link bar 35.

At the same time that the latch pin 37 of the right balanced lever system 29 is in the latching position shown in Fig. 3, the latch pin 37 of the similarly constructed left balanced lever system 28 (Fig. 4) is in an unlatching position at the opposite end of the associated circumferential slot 38 in left cam plate 11 from radial slot 39 therein. This is because the left and right balanced lever systems 28 and 29 are reversed relative to each other, and because the radial slot 39 of left cam plate 11 is at the opposite end of its associated circumferential slot 38 from the radial slot 40 of right cam plate 12. When the left balanced lever system 28 is in unlatching position as shown in Fig. 4, the latch pin 37 thereof is depressed and the lever system 28 pivoted against the bias of tension springs 41 to space the stop arms 43 of link bars 34 and 35 from each other.

In order to rotate the interconnected left and right cam plates 11 and 12 from the reverse rotated or circuit closing positions illustrated in Figs. 3 and 4 to the forward rotated or circuit opening positions shown in Fig. 6, it is first necessary to depress the latch pin 37 of the right balanced lever system 29 into the circumferential slot 38 of right cam plate 12. This moves the pin 37 out of the path of the end of an arm member 44, the latter forming the portion of cam plate 12 outwardly of circumferential slot 38. The cam plates are then free to rotate forwardly, either as the result of manual depression of the front actuating member 6 or of operation of the overload devices 26 and 27 as will be described subsequently. During such forward rotation the latch pin 37 of right balanced lever system 29 rides along the under edge of arm 44, as a result of the bias of tension springs 41, and the corresponding pin 37 of left balanced lever system 28 similarly rides along the under edge of a corresponding and oppositely extending arm 45 of left cam plate 11. After the cam plates have been rotated to their forward position, latch pin 37 of left balanced lever system 28 is in registry with radial slot 39 of left cam plate 11 and is actuated outwardly by tension springs 41 to the locking position illustrated in Fig. 6. The left and right balanced lever systems and cam plates have thus in effect exchanged positions, so that the left balanced lever system 28 is shifted to latch the plates in forward rotated position whereas the right balanced lever system 29 is shifted to unlatching position.

The necessary depression of the latch pins 37 to permit forward and reverse rotation of cam plates 11 and 12 is accomplished by means of a pair of lug members 46 and 47 which extend inwardly from the respective front and rear switch actuating members 6 and 7. The lug 46 associated with front actuating member 6 is disposed above a pair of ears 48 formed integral above the latch pin 37 of right balanced lever system 29 with the components of the upper lever link 31 thereof. Correspondingly, the lug 47 associated with rear actuating member 7 is disposed above similarly located ears 49 of the left balanced lever system 28. The lug members 46 and 47 are formed integral, respectively, with a pair of plate-like mounting members 50 which are secured by screws to the undersides of the push buttons 10.

The push buttons 10, which are preferably formed of a plastic insulating material, are each shaped with a hollow generally cylindrical portion 51 adapted to extend upwardly through a corresponding aperture in frame channel member 5, and with forwardly and rearwardly extending mounting portions 52 adapted to receive the screws securing the associated mounting member 50 in position. As shown in Figs. 1 and 3, the cylindrical chamber within each button portion 51 serves to receive one of the springs 39, the latter being compressed between the upper button end and an upright cup 53 which is slidably mounted within the chamber.

Each cup 53 is secured as by welding to the upper end of a vertical arm bar 9, there being a slot in mounting member 50 through which the arm bar 9 projects. A lost motion and spring loading arrangement is thus provided whereby the manual depression of a push button 10 causes the button to move relative to its associated cup 53 and arm bar 9 and additionally compress spring 39. Such compressing action continues,

for example in the set of elements shown in Fig. 3, until the lug member 46 engages ears 48 to depress latch pin 37 and move the same out of latching engagement with the end of arm 44. Immediately upon the occurrence of unlatching, that is to say as soon as pin 37 is depressed into circumferential slot 38, the cam plates 11 and 12 are snapped forwardly due to the sudden release of the energy stored in spring 30 during the initial button movement prior to unlatching. The front vertical arm bar 9, through which the energy of the spring 30 is transferred via rivet member 15 to the unlatched cam plates, is thus depressed from the elevated position shown in Fig. 3 to a position lower than that of the arm bar of the rear actuating member 7.

In addition to their function of providing snap-action shifting, the spring portions 30 of the front and rear actuating members 6 and 7 serve, together with the balanced lever systems 28 and 29, to prevent unlatching of the cam plates as the result of shock. This is because any shock actuation of push buttons 10 and lugs 46 and 47 is completely stopped by springs 30 prior to the unlatching engagement of ears 48 and 49. After the shock, therefore, the buttons 10 snap back to the desired positions as the result of the energy stored in springs 30, there having been no switching action performed.

As mentioned previously, the switch is constructed to be operated not only by the front and rear actuating members 6 and 7 but by a pair of assemblies 26 and 27 connected to respond to the flow of overload currents in the circuits controlled by contact assembly 8. The overload devices each comprise a generally rectangular base 54 which is secured by the screws 3 to the upper surface of a side plate flange 4, and a thermal responsive means including a ratchet wheel 55 arranged at the inner face of the base 54 and a solder element 56 disposed in the communicating recessed outer portion thereof.

Referring particularly to Figs. 7 and 10, each solder element 56 includes a small sleeve or cylinder 57 which is non-rotatably connected to a base 54 as by interlocking with a bracket member 58 mounted on the base. A piston or core member 59, mounted at the outer end of cylinder 57 within a non-rotatable cup 60 therein, is connected by a rod 61 to the ratchet wheel 55, there being a retaining ring interposed to prevent axial shifting of the core 59 and ratchet member. Suitable solder, not shown, is provided between the core 59 and cup 60 to lock the ratchet wheel 55 against rotation at all times except when the solder is melted. Such melting is performed by a heating coil, not shown, which is connected into a circuit controlled by contact assembly 8 and is coiled around the cylinder 57. The construction of the solder element is such that the solder does not flow out of place when melted but instead remains between the piston 59 and cup 60, so that the ratchet wheel is again locked against rotation upon cessation of the flow of overload current in the heating coil.

As best shown in Figs. 1, 6 and 8, the normally locked ratchet wheels 55 are associated by means of pawls 62 with a pair of levers 63 and 64 which are pivotally mounted outwardly adjacent side plates 2 on a fulcrum pin 65 extending between and through the lower rear portions of the side plates. The pawls are secured, respectively, on the outer faces of the levers 63 and 64 and extend rearwardly to engage with their downwardly hooked end portions the teeth of ratchet wheels

55. Contrary to the case of the base member 54 and levers 63 and 64 which are molded of an insulating plastic material, the pawls 62 are formed of a suitable spring metal.

5 In order to bias the levers 63 and 64 upwardly, or counterclockwise in Fig. 6, a pair of compression springs 66 are mounted, respectively, between lug portions 67 formed at the lower edges of the levers forwardly of fulcrum pin 65 and vertical studs 68 provided on base plate 1. Each stud 68 extends into a large opening 69 cut both in the vertical portions of side plates 2 and in the horizontal flanges 4 thereof.

15 The teeth of the ratchet wheels 55 of both left and right overload devices 26 and 27 are formed in a manner to permit downward pivot of the left and right levers 63 and 64 but to prevent upward pivot thereof. Accordingly, the levers are normally maintained in a depressed position against the bias of springs 66 until melting of the solder in solder elements 56 permits turning of the ratchet wheels 55 and upward pivot of the levers. The levers 63 and 64 may be reset to downward pivoted position merely by depressing the same, the ratchet teeth then being inoperative to prevent movement of the pawls 62 relative thereto.

20 Referring to Figs. 1, 2 and 5 wherein the lever 64 of the right overload device 27 is shown, a portion 70 of lever 64 is shaped to extend inwardly through a side plate opening 69 for actuating engagement with the right balanced lever system 29. For this purpose a horizontal shelf 71 is provided on the lever portion 70 beneath a pair of ears 72, the latter being integral with the components of the lower lever link 32 of the right lever system 29. Assuming that the cam plates 11 and 12 are in their rearward pivoted positions as shown in Fig. 3, so that the right balanced lever system 29 is in latching condition and the contact assembly 8 is in circuit closing position, the upward pivot of the right overload lever 64 resulting from melting of the solder in the associated solder element 56 will cause the shelf 71 to engage and actuate the right ear 72 upwardly. The lower lever link 32 will thus rotate clockwise, which operates through balanced lever system members 33, 34 and 35 to pivot the upper lever link 31 clockwise and depress the latch lug 37 into unlatching position in circumferential slot 38. In order to pivot the cam plates 11 and 12 forwardly to effect opening of the circuits controlled by contact assembly 8 once such unlatching is accomplished, a spring 73 (Figs. 1 and 3) is provided between the cam plates on a spacer on axle member 14. The spring 73, which is coiled around the spacer, is hooked at one end over the front rivet member 15 and is hooked at the other end under a pin 74 extending between the front upper portions of side plates 2.

25 Referring to Figs. 1, 4, and 5, the left overload lever 63 is adapted to similarly effect forward pivot of the cam plates 11 and 12 and consequent shifting of the contact assembly 8 to circuit opening condition for cessation of the flow of overload current. For this purpose the lever 63 is provided with a portion 75 which extends inwardly through an opening 69 and terminates in a small cylindrical lug 76. The lug 76 is inserted through a corresponding aperture in one arm 77 of a generally U-shaped lever member 78 which is pivoted on fulcrum pin 65, so that upward pivot of the overload lever 63 causes upward pivot of the lever 78. As best shown in

Fig. 5, the base or rear portion 79 of the U-shaped lever 78 extends laterally behind fulcrum pin 65 to interconnect the arm 77 with a corresponding forwardly extending arm 80 disposed on the right side of the switch. The arm 80 terminates at its forward end, generally opposite lug 76, in a raised shelf portion 81 disposed beneath the left ear 72 of right balanced lever system 29 adjacent shelf 71 of right overload lever 64. Accordingly, the right balanced lever system 29 may be actuated to unlatching position by the shelf portion 81 of U-shaped lever 78 in the same manner as by the shelf 71 of right overload lever 64.

In order to more rigidly interconnect the arms 77 and 80 of U-shaped lever 78, and also to brace the lever against shock, a horizontal pan portion 82 is provided between the lower and rear edges of the arms 77 and 80 and along the lever base 79. The pan 82 is shaped with a slot 83 to receive an angle bracket 84 which is mounted on base plate 1 and adapted to reinforce fulcrum pin 65 against bowing under shock conditions.

The construction, mounting, and operation of the overload devices 26 and 27 and associated parts is such that the possibility of undesired unlatching of the cam plates 11 and 12 and consequent operation of the contact assembly 8 is minimized. A percussive shock for example, would not shift shelf 71 or shelf 81 to actuate the right balanced lever system 29 to unlatching position since the shelves are effectively locked in place by the solder elements 56 acting through the pawl and ratchet assemblies and through levers 63, 64 and 78. Also, the fact that the overload devices 26 and 27 act through a balanced lever system 29 results in a shock resistant remote control arrangement permitting the overload devices to be rigidly mounted as a unit with the lower frame portions of the switch, where they do not interfere with manual snap-action switch operation and where they may be easily reset by the front switch actuating member 6 as will next be described.

The left and right overload devices 26 and 27 are adapted to effect unlatching of the cam plates 11 and 12 either in cooperation with each other or independently, depending upon the manner in which the heating coils which melt the solder in solder elements 56 are connected. In Fig. 6 for example, the left overload lever 63 is illustrated as having effected actuation of the cam plates to forward or clockwise pivoted position whereas the right lever 64 is still in a depressed position. In order to either simultaneously or separately reset the overload levers to depressed positions, a resetting lever 85 is pivotally mounted on fulcrum pin 65 between the arms 77 and 80 of U-shaped lever 78.

Referring to Figs. 3 and 5, the lever 85 which is utilized to reset the overload levers 63 and 64 to their depressed positions is constructed with a pair of spaced parallel side members 86 having their rear ends pivoted on pin 65 and their relatively narrow forward ends formed integral with inwardly bent overlapping portions 87 which are welded together to connect the side members. A channel bar 88 is secured transversely above the mid portions of the members, for example by welding to opposed inwardly extending tabs thereon, and is adapted to engage the upper edges of both arms 77 and 80 of U-shaped lever 78. In addition, the right end of the channel bar 88 is disposed to engage a second shelf portion 89 of right overload lever 64, the shelf 89 being to the

rear and beneath the first shelf 70 of said lever. To insure that the channel bar 88 and other resetting elements remain in the proper lateral positions, suitable spacing cylinders are provided 5 along fulcrum pin 65 as shown in Fig. 5, and a laterally extending portion 90 is formed integral with the left side member 86 of resetting lever 85 and shaped to bear against the left arm 77 of lever 78.

10 The overlapping front portions 87 of resetting lever 85 are disposed (Fig. 3) beneath the lower end of the relatively long arm bar 9 of front actuating member 6, there being a portion cut out 15 of the lower front portion of the arm to permit depression thereof to engage resetting lever portions 87 without interference by the fulcrum pin 19 and the associated lever sides 18 between which the bar 9 passes. When the resetting lever portions 87 are engaged upon downward movement of front arm bar 9, the resetting lever is pivoted downwardly to depress channel bar 88. The overload levers 63 and 64 are thus pivoted 20 downwardly and reset, either directly as in the case of right lever 64 which is engaged at shelf 25 89 by the channel bar 88, or indirectly as in the case of left lever 63 which is reset by the channel bar acting through U-shaped lever 78.

In the operation of the resetting means, assume that the cam plates 11 and 12 are in their 30 rearward pivoted positions, so that the contact assembly 8 is maintained in circuit closing position by the connecting lever 13. Upon the occurrence of an overload one or more of the solder elements 56 will melt to release the associated 35 lever 63 or 64 for upward pivot under the bias of a spring 66 until ears 72 on right balanced lever system 29 are engaged and actuated. The associated right latch pin 37 will thus be depressed to permit forward pivot of cam plates 11 and 12 40 under the bias of spring 73, and the resetting lever 85 will be pivoted to its uppermost position (Fig. 6) due to lifting of channel bar 88 by one or more of the overload levers. Such forward pivoting of the cam plates 11 and 12 and substantially simultaneous upward pivoting of the 45 resetting lever 85 is possible because of the described lost motion connection between the front vertical arm bar 9 and the rivet member 15 connecting the cam plates.

Upon cessation of the overload condition the 50 front actuating member 6 may be depressed, which operates through arm bar 9 thereof to pivot the lever 85 downwardly and reset the overload levers 63 and 64 to downward pivoted positions. The normal manual operation of the 55 switch may then be resumed, for example by depressing the rear actuating member 7 to effect backward pivot of the cam plates 11 and 12 and consequent operation of the contact assembly 8 to circuit closing position. Even if the overload condition has not been corrected, the switch may be maintained in circuit closing condition for emergency operation by manually maintaining the rear actuating member 7 in depressed condition. The continued depression of rear actuating member 7 prevents forward pivot of cam plates 11 and 12 under the bias of spring 73 after unlatching operation of the overload devices as a result of the overload.

70 The contact assembly 8, which is actuated between circuit opening and closing positions by the elements set forth heretofore, is substantially identical, except for adjustment and index means to be described subsequently, with the assembly 75 illustrated and claimed in U. S. Patent 2,532,305

for an Electric Switch, issued to Herbert E. Heller on December 5, 1950.

Referring to Figs. 9 and 10, the contact assembly comprises a housing or contact supporting member 91 which is vertically mounted at the rear of the frame and is shaped with an internal guideway 92 in which the slide bar 21 is vertically movable. Both the housing 91 and slide bar 21 are molded of a suitable insulating material, as is a cover member 93 which is secured over the rear of the housing. The housing 91 serves as a support for three vertically spaced pairs of opposed stationary contact members 94 having terminal extensions 95 which project outwardly through openings in the housing. The means for securing the contact members 94 to the housing may comprise screws 96 located midway between the terminal extensions 95 and the inner or contact ends of the members 94.

The slide bar 21 is provided with three vertically spaced rectangular apertures 97 to receive transversely extending bridging contactor bars 98 which cooperate with the contact ends of contact members 94 in opening and closing circuits between the terminal extensions 95. In order to bias the contactor bars 98 downwardly into engagement with the contact members 94 when the slide bar 21 is in its lower position, a helical compression spring 99 is mounted in each aperture 97 over centrally disposed vertical end projections 100 and 101 which are formed, respectively, on the upper and lower walls of the aperture. The end projections are of elliptoid shape and extend lengthwise between the open ends of the apertures, so that each lower end projection 101 may project through a guide opening in the associated contactor bar 98 and maintain the same in the correct transverse position.

As shown in Fig. 6, when the slide bar 21 is in elevated position the contactor bars 98 are spaced from the stationary contact members 94 and are biased downwardly by springs 99 against stop portions 102 formed in the apertures 97. Upon downward sliding of the bar 21 to the lower or circuit closing position illustrated in Figs. 9 and 10, the respective contactors 98 engage the contact ends of contact members 94 and are relatively lifted off the stop portions 102 against the bias of springs 99. The shifting of the contactor bar 21 between its upper or circuit opening position and its lower or circuit closing position is effected by the rear end of the connecting lever member 13 which projects through an opening in contact housing 91 and into a suitable recess 103 in the lower end of the slide bar 21.

The slide bar recess 103 is only slightly larger than the roller 20 which is mounted at the rear end of connecting lever 13, so that when the lever is locked in its upper or lower position by the latching and cam means previously described the slide bar may not be shifted, for example as the result of shock, to undesired switching positions. The precise upper or lower position of the lever 13, roller 20 and slide bar 21 relative to the frame of the switch varies between switches, however, as the result of manufacturing tolerances.

Because of the fact that the circuit opening and closing positions of the slide bar 21 relative to the frame of the switch vary from switch to switch due to tolerances in the manufacture of the switch components, it becomes necessary to provide means for obtaining a desired uniform wear allowance in all switches manufactured in accordance with the invention. The wear allow-

ance may be defined as the amount that the contacting faces of contactor bars 98, and also of contact members 94, must wear or burn off before the bars 98 engage the stop portions 102 of the slide bar 21 when the slide bar is in the lower or circuit closing position shown in Figs. 9 and 10. If the wear allowance is too small, that is to say if a new contactor bar 98 is only lifted a slight distance off a stop portion 102 when the switch is closed, the contactor bar will engage stop 102 after only slight wear of the contact faces and the life of the contactor bar will be unnecessarily shortened. If, on the other hand, the wear allowance is too large, improper switching will result after the wearing off of an excessive amount of the contacting faces.

According to the invention, means are provided to initially adjust the contact housing 91 relative to the frame of the switch and to indicate when such adjustment has produced the correct wear allowance in the contactor bars 98.

The adjustment means comprises a plurality of horizontally stacked shims 104, which are disposed between an overhanging ledge portion 105 (Fig. 10) of the housing 91 and the upper rear portion of the frame channel member 5, and a pair of vertically elongated screw holes 106 provided through the lower corners of the housing. The holes 106 permit vertical adjustment of the housing 91 relative to mounting screws 107 which extend forwardly through the holes and into vertical flanges 108 on the rear edges of frame portions 4. The ledge portion 105 and shims are apertured to receive a pair of downwardly extending mounting screws 109 which are threaded into frame portion 5.

In the adjustment of the contact assembly 8 for the desired wear allowance, the switch is first operated to its circuit closing position illustrated in Fig. 10. The screws 107 are then loosened and a sufficient number of shims 104 are inserted to cause the lower edges of contactor bars 98 to register with raised index or reference marks 110 which are formed at predetermined points on the sides of the slide bar 21. The screws 107 are then tightened and the screws 109 are inserted and tightened to rigidly lock the contact housing 91 in the correct position. With such an adjustment arrangement, variations between switches in the position of the slide bar 21 relative to the frame are easily compensated for by corresponding variations in the position of the contact supporting member 91 relative thereto.

The operation of the switch, after the same has been initially adjusted to the proper wear allowance as described, will next be summarized.

Assume that the switch is in its closed position, as illustrated in Figs. 1-4, 9 and 10. The cam plates 11 and 12 are then in their reverse rotated positions, that is to say counterclockwise rotated in Fig. 3, and the lever member 13 is pivoted downwardly to hold the slide bar 21 in a depressed condition and cause the contactors 98 to be in engagement with contact members 94. In addition, the right balanced lever system 29 is in latching condition with the latch pin 37 thereof in the radial slot 40 of right cam plate 12.

In order to manually actuate the switch to circuit opening position, the operator presses downwardly on the push button 10 of front actuating member 6. This moves the button relative to the associated arm bar 9 until the lug member 46 engages ears 48 to depress the same

13

and force right latch pin 37 downwardly to unlatching position against the bias of tension springs 41. Immediately upon completion of such unlatching movement, the cam plates 11 and 12 are snapped forwardly due to the sudden release of energy stored in the front spring 39 during unlatching, with the spring acting on the cam plates via front arm bar 9 which engages at the upper end of slot 25 the rivet member 15. During the forward pivot of the cam plates, the connecting lever 13 is pivoted upwardly as the cam pin 22 thereon rides in the cam slots 24 of the plates 11 and 12, so that the slide bar 21 is lifted to disengage the contactors 98 from contact members 94 and open the switch. At the completion of the forward pivot of the cam plates, the latch pin 37 of left balanced lever system 28 is actuated upwardly by tension springs 41 thereof to latching position within the radial slot 39 of left cam plate 11. As shown in Fig. 6, additional upward movement of the left latch pin 37 past the end of arm member 45 is prevented due to the engagement of the stop arms 43 of forward and rear vertical lever system members 34 and 35 with each other.

To actuate the switch to closed position the button 10 of rear actuating member 7 is depressed, causing lug member 47 thereon to engage the ears 49 of left balanced lever system 28 and force the latch pin 37 thereof into the associated circumferential slot 38. As in the case of the operation of the switch to open position, the cam plates 11 and 12 are then snapped rearwardly because of the sudden release of the energy of rear spring 30 upon unlatching of the left balanced lever system. This rearward motion, effected by the pivotal connection between rear vertical arm 9 and rivet member 16, causes downward pivot of connecting lever 13 due to the movement of cam pin 22 within cam slots 24. Slide bar 21 is thus snapped downwardly to its lower position, shown in Figs. 9 and 10, at which time the contactors 98 are in biased engagement with contact members 94. The right balanced lever system 29 then being in latching position as before, the switch tends to remain in closed condition despite the effects of percussive shock.

When the switch is in this circuit closing position, an overload condition may occur in the circuits controlled by contact assembly 8, which will cause one or more of the overload devices 26 and 27 to actuate the switch to circuit opening position in the following manner. Referring to Figs. 1, 5, 7, 8 and 10, the flow of overload current in a circuit controlled by contact assembly 8 may cause, depending upon how the overload devices are connected, a heating coil, not shown, to melt the solder of the solder element 56 of left overload device 26. The melting of the solder will release the associated ratchet wheel 55 for rotational movement, so that it becomes inoperative to prevent upward movement of the pawl 62 engaged therewith under the bias of the left compression spring 66 acting on the left lever member 63. As the left lever 63 snaps to its upper position, shown in Fig. 6, the U-shaped lever member 78 is also moved upwardly due to the mounting of lug 76 through the aperture in the left arm 77 of lever 78. As the U-shaped lever 78 approaches its uppermost position, the shelf portion 81 thereof engages an ear 72 of right balanced lever system 29 and actuates the same upwardly. This in turn effects downward actuation of the latch pin 37 of the right balanced lever system into unlatching condition within

14

circumferential slot 38 of right cam plate 12, the cam plates 11 and 12 then being free to pivot forwardly or clockwise in Fig. 3 under the bias of spring 73 acting on forward rivet member 15. Since the cam plates 11 and 12 are pivoted forwardly, the connecting lever 13 is operated to its upper position to lift the slide bar 21 and open the switch, as in the case of manual operation of the switch through the depression of front actuating member 6.

Similarly to the case of the left overload device 26, the right overload device 27 is responsive to an overload condition in its circuit, which results in the melting of the solder element 56 thereof and consequent freeing of the right ratchet wheel to permit upward pivot of right overload lever member 64 under the bias of the spring 66 therebeneath. The horizontal shelf 71 of the right lever member 64 is thus engaged with an ear 72 to unlatch the switch for movement to circuit opening position as in the case of actuation of an ear 72 by the shelf 81 of U-shaped lever 78.

As one or the other of the left and right overloading levers 63 or 64 pivot upwardly to effect opening of the switch, the channel bar 88 of resetting lever 85 is lifted due to engagement thereof by shelf 89 of the right overload lever 64 or by the arms 77 and 89 of the U-shaped lever 78 operated by the left overload lever 63. The vertical arm 9 of front actuating member 6 is thus maintained in its elevated position, shown in Fig. 6, due to engagement of the resetting lever portions 87 with the lower end thereof. Since the front actuating arm 9 is maintained stationary while the cam plates 11 and 12 pivot forwardly, the rivet member 15 moves downwardly relative to the vertical slot 25 in the arm bar.

In order to reset the actuated overload device 26 or 27, it is merely necessary to depress front actuating member 6 and thus pivot the resetting lever 85 downwardly. The channel bar 88 will then depress the overload levers 63 and 64, and they will remain in depressed condition due to the locking of their associating pawls 62 by the ratchet wheels 55, the ratchet wheels then being locked in position due to freezing of the solder in elements 56 upon cessation of the flow of overload current. Regardless of whether the solder is melted and the overloads actuated, the switch may be maintained in circuit closing position for emergency operation by holding the rear actuating member 6 in a depressed position.

The invention provides a compact switching unit which is constructed for maximum resistance to percussive shocks, and which is both manually operable and operable in response to overloads in the circuits controlled thereby. Because of the fact that a balanced lever system is employed as a shock resistant remote control means by which the current responsive devices effect unlatching operation upon the occurrence of an overload, the current responsive devices may be conveniently and rigidly mounted a substantial distance from the members which latch the switch in its open and closed positions.

Although the invention has been shown and described with the pushbuttons and contact structure in a vertical position, it should be understood that this was done for ease of description only. Under normal circumstances the switch will be mounted so that the pushbuttons and contact structure are in horizontal position.

Various embodiments of the invention may be

15

employed within the scope of the following claims.

We claim:

1. In a shock resistant starter switch, contact means, shifting means operatively connected with said contact means, said shifting means being movable between a first position effecting a first circuit controlling condition in said contact means and a second position effecting a second circuit controlling condition therein, a balanced lever system including a latch portion adapted to latch said shifting means in said first position and thus insure maintenance of said contact means in said first circuit controlling condition, and means for effecting unlatching operation of said balanced lever system and movement of said shifting means from said first position to said second position.

2. In a shock resistant starter switch, contactor means, intermediate means operatively associated with said contactor means and movable to shift the same between first and second circuit controlling positions, a balanced lever system comprising portions of substantially equal shock susceptibility balanced on opposite sides of a fulcrum and including latch means adapted when said lever system is in a given position to latch said intermediate means against shifting movement, and means to actuate said latch means and balanced lever system to an unlatching position and to move said intermediate means for shifting of said contactor means between said first and second positions.

3. In a shock resistant starter switch, contact means, intermediate means operatively associated with said contact means and movable to shift the same between first and second circuit controlling positions, balanced lever means having latch means adapted when said balanced lever means is in a given position to latch said intermediate means and thus prevent shifting of said contact means, and manually operable actuating means to actuate said latch means to an unlatching position and to move said intermediate means for shifting of said contact means between said first and second positions, said actuating means including a lost motion and spring loading portion effecting snap-action movement of said intermediate means and contact means upon operation of said latch means to unlatching position.

4. A shock resistant starter switch, comprising electrical contact means, intermediate means connected to said contact means and movable to shift the same to a plurality of circuit controlling positions, a balanced lever system including a latch portion adapted to latch said intermediate means against shifting movement, manual means adapted to actuate said balanced lever system on one side of the principal fulcrum thereof to thereby effect unlatching operation of said latch portion and permit shifting movement of said intermediate means, and current responsive means adapted to actuate said balanced lever system on the opposite side of said principal fulcrum thereof to similarly effect unlatching operation of said latch portion in the event of an overload in the circuit controlled by said contact means.

5. In a starter switch, electrical contact means, intermediate means operably associated with said contact means and movable between a first position effecting closing of said contact means and a second position effecting opening of said contact means, means to latch said intermediate

16

means in each of said positions, and manually operable means to effect unlatching operation of said latch means and to move said intermediate means between said first and second positions for opening and closing of said contact means.

6. A shock resistant switch, comprising electrical contacts, intermediate means connected with said contacts and movable between a first position effecting closing of said contacts and a second position effecting opening thereof, a first balanced lever system having a latch portion adapted to latch said intermediate means in said first position, a second balanced lever system having a latch portion adapted to latch said intermediate means in said second position, first manually operable means to effect unlatching operation of said second balanced lever system and shift said intermediate means to said first position, and second manually operable means to effect unlatching operation of said first balanced lever system and shift said intermediate means to said second position.

7. A shock resistant starter switch, comprising electrical contact means, intermediate means operably associated with said contact means and movable between a first position effecting closing of said contact means and a second position effecting opening thereof, balanced lever means, means on said balanced lever means and intermediate means to alternately latch said intermediate means in said first and second positions, a pair of actuating arms operably associated with said intermediate means to move the same between said positions, a pair of manually operable members mounted, respectively, at the ends of said actuating arms and movable relative thereto, said manually operable members being disposed to actuate said balanced lever means and latch means to unlatching condition after predetermined movements relative to said actuating arms, and a pair of springs mounted, respectively, between said actuating arms and manually operable members for loading during said predetermined movements, said balanced lever means and said springs serving to prevent undesired actuation of said latch means to unlatching condition as a result of percussive shocks.

8. A starter switch, comprising a frame, an intermediate member rotatably mounted on said frame, electrical contact means mounted on said frame, a lever pivotally connected to said frame and operably associated with said contact means to shift the same between open and closed conditions, means interconnecting said intermediate member and said lever and effecting operation of said lever to open said contact means upon rotation of said intermediate member to a first position and to close said contact means upon rotation of said intermediate member to a second position, means to latch said intermediate member in at least one of said positions, and manually operable means to effect unlatching operation of said latch means and to rotate said intermediate member to the other of said positions.

9. A shock resistant switch, comprising a frame, a cam plate mounted in said frame for rotation about an axis transverse to said cam plate, electrical contact means mounted on said frame, a connecting lever associated with said contact means to shift the same between open and closed conditions, cam means interconnecting said cam plate and said lever and effecting operation of said lever to open said contact means upon rota-

tion of said plate member to a first position and to close said contact means upon reverse rotation of said cam plate to a second position, a lever system comprising corresponding portions of substantially equal shock susceptibility balanced on opposite sides of a fulcrum, a latch member mounted on said lever system and adapted to extend into a radial opening in said cam plate to latch the same in one of said positions, and an actuating arm adapted firstly to actuate said lever system and effect movement of said latch member out of said radial opening and secondly to actuate said cam plate to the other of said positions.

10. A shock resistant starter switch, comprising a frame, a plate member mounted on said frame and rotatable about an axis transverse to said plate member, an electrical contact assembly mounted adjacent said frame, a connecting member operatively associated with said contact assembly, said connecting member being operated by said plate member and effecting shifting of said contact assembly to one circuit controlling condition upon rotation of said plate member to a first position and shifting of said contact assembly to another circuit controlling condition upon reverse rotation of said plate member to a second position, first and second balanced lever systems including latch portions adapted, respectively, to latch said plate member in said first and second positions, first and second actuating members associated with said plate member and manually operable, respectively, to shift the same to said first and second positions, first and second button means associated, respectively, with said first and second actuating members and movable relative thereto, said first button means being adapted after a predetermined initial movement relative to said first actuating member to actuate said second balanced lever system to unlatching condition, said second button means being adapted after a predetermined initial movement relative to said second actuating member to actuate said first balanced lever system to unlatching condition, and compression spring means interposed, respectively, between said first and second button means and said first and second actuating members to effect snap action shifting of said plate member after operation of said balanced lever systems to unlatched conditions by said button means, said spring means and said balanced lever systems insuring maintenance of said contact assembly in the desired circuit controlling condition until manual actuation of said button means by the operator of the switch.

11. A shock resistant switch, comprising a frame, a cam element mounted on said frame for rotation about an axis normal to said cam element, an electrical contactor assembly mounted on said frame, a connecting lever associated with said contactor assembly to shift the same between open and closed conditions, cam means interconnecting said cam element and said lever and effecting operation of said lever to open said contactor assembly upon rotation of said cam element to a first position and to close said contactor assembly upon rotation of said cam element to a second position, first and second balanced lever systems mounted on said frame adjacent said cam element, said lever systems each comprising portions of substantially the same shock susceptibility arranged on opposite sides of a principal fulcrum, a first latch means interconnecting said first balanced lever system and

said cam element to latch said cam element in said first position, second latch means interconnecting said second balanced lever system and said cam element to latch said cam element in said second position, first manual means to actuate said first balanced lever system and first latch means to unlatching condition for shifting of said cam element to said second position, second manual means to actuate said second balanced lever system on one side of the principal fulcrum and effect unlatching operation of said second latch means for shifting of said cam element to said first position, and a solder type overload device mounted on said frame and connected to respond to the flow of overload current in a circuit controlled by said contactor assembly, said overload device being disposed to actuate said second balanced lever system on the opposite side of the principal fulcrum thereof from the point of actuation of said second manual means and to similarly effect unlatching operation of said second latch means for shifting of said cam element to said first position and opening of said contactor assembly.

15. A shock resistant starter switch, comprising electrical contact means, intermediate means connected to said contact means and movable to a first position effecting opening of said contact means and a second position effecting closing thereof, first and second balanced lever systems including latch portions adapted, respectively, to latch said intermediate means in said first and second positions, manual means including a spring loading and lost motion portion operable to actuate said second balanced lever system on one side of the principal fulcrum thereof to unlatch said intermediate means, said manual means being operable to effect snap-action shifting movement of said intermediate means after unlatching thereof, and current responsive means adapted to actuate said second balanced lever system on the opposite side of said principal fulcrum thereof to similarly unlatch said intermediate means in the event of an overload in the circuit controlled by said contact means, said current responsive means being adapted to be reset to normal position by said manual means.

20. A shock resistant switch, comprising a frame, an axle member mounted in said frame, a pair of rigidly interconnected spaced parallel cam plates mounted on said axle member for pivotal movement thereabout, an electrical contact assembly mounted on said frame and including a contactor bar slidable between circuit opening and circuit closing conditions, a lever member having one end disposed in a corresponding recess in said slidable contactor bar and extending between said cam plates for pivotal connection at its other end to said frame, a cam pin mounted transversely of said lever member and extending into cam slots in said cam plates, said cam pin and cam slots effecting pivot of said lever member to actuate said contactor bar to circuit opening condition upon rotation of said cam plates to a first position and effecting pivot of said lever member to actuate said contactor bar to circuit closing condition upon reverse rotation of said cam plates to a second position, first and second balanced lever systems mounted on said axle member adjacent the outer surfaces of the respective cam plates and being reversed relative to each other, a first latch lug mounted on said first balanced lever system and adapted to alternately extend into a circumferential slot in one of said cam plates and into

a communicating radial slot in said one cam plate depending upon the rotated position thereof, a second latch lug mounted on said second balanced lever system and adapted to alternately extend into a corresponding circumferential slot in the other of said cam plates and into a communicating radial slot in said other cam plate depending upon the rotated position thereof, said radial slots being at opposite ends of said corresponding circumferential slots, spring means to bias said first balanced lever system in a direction effecting latching location of said first latch lug in the associated radial slot upon rotation of said cam plates to said first position and to bias said second balanced lever system in a direction effecting latching location of said second lug in the associated radial slot upon reverse rotation of said cam plates to said second position, a first actuating arm extending between said cam plates and pivotally connected thereto on one side of said axle member, a first spring loaded push button mounted for movement relative to said first actuating arm, means on said first push button to engage said first balanced lever system adjacent said first latch lug and effect movement of said lug to unlatching position within the associated circumferential slot and free said cam plates for shifting to said second position, a pair of spring biased ratchet type current responsive devices mounted on said frame and adapted to engage said second balanced lever system on the opposite side of said axle member from said second latch lug and effect movement of said lug to unlatching position within the associated circumferential slot, spring means to rotate said cam plates to said first position upon unlatching thereof by said current responsive devices, a second actuating arm extending between said cam plates and pivotally connected thereto by a lost motion connection disposed on the opposite side of said axle member from said first actuating arm, a second spring loaded push button mounted for movement relative to said second actuating arm, means on said second push button to engage said second balanced lever system adjacent said second latch lug and effect movement of said lug to unlatching position within the associated circumferential slot and free said cam plates for shifting to said first position, and a resetting lever pivotedly connected to said frame and having portions disposed for actuation by said second actuating to reset said current responsive devices to the normal positions thereof.

14. A shock proof starter switch, comprising a frame, a contact housing mounted adjacent said frame, a plurality of electrical contacts rigidly mounted in said housing and movable therewith, a slide bar mounted in said housing and slideable relative thereto, a plurality of electrical contactors movably mounted on said slide bar and disposed, respectively, in engagement with said contacts when said slide bar is in circuit closing position and out of engagement with said contacts when said slide bar is in circuit opening position, spring means disposed, respectively, between said contactors and slide bar to bias said contactors against said contacts when said slide bar is in circuit closing position, slide bar actuating means mounted on said frame and operatively associated with said slide bar to actuate the same

between circuit opening and circuit closing positions, balanced lever type latch means mounted on said frame and adapted to latch said actuating means at a position effecting location of said slide bar at said circuit closing position, said circuit closing position varying relative to said frame in accordance with the manufacturing tolerances of the slide bar actuating means and latch means, index means provided on said slide bar, and means to adjust the position of said contact housing relative to said frame for correlation of the positions of said contactors and said index means when said slide bar is in said circuit closing position, said index means and adjusting means making possible the achievement of a predetermined wear allowance in said contactors despite said variations in the circuit closing position of said slide bar.

15. A shock resistant actuating mechanism comprising, in combination, a movable element, means movable to first and second positions adapted for moving said element, said means including a pair of rotatably mounted rigidly interconnected spaced parallel plates; first and second balanced lever systems concentrically mounted adjacent the outer surfaces of the respective cam plates and being reversed relative to each other; a first latch pin mounted on said first balanced lever system and adapted to alternately extend into a circumferential slot in one of said plates and into a communicating radial slot in said one plate depending upon the rotated position thereof; a second latch pin mounted on said second balanced lever system and adapted to alternately extend into a corresponding circumferential slot in the other of said plates and into a communicating radial slot in said other plate depending upon the rotated position thereof, said radial slots being at opposite ends of said corresponding circumferential slots; spring means biasing each of said latch pins toward said radial slots; and actuating means for moving said balanced lever systems to unlatching position and to move said plates to effect movement of said movable element.

16. A shock resistant actuating mechanism according to claim 15, wherein said actuating means comprises a pair of actuating arms operably associated with said movable means to move the same between said positions; a pair of manually operable members mounted, respectively, at the ends of said actuating arms and movable relatively thereto, said manually operable members being disposed to actuate said balanced lever means to unlatching condition after predetermined movements relatively to said actuating arms; and a pair of springs mounted, respectively, between said actuating arms and manually operable members for loading during said predetermined movements, said balanced lever systems and said springs serving to prevent undesired actuation of said latch means to unlatching condition by percussive shocks.
